UNITED STATES PATENT OFFICE.

JOHN ANGELL, OF ST. LOUIS, MISSOURI.

FEED-WATER HEATER AND PURIFIER.

SPECIFICATION forming part of Letters Patent No. 738,751, dated September 15, 1903.

Application filed April 27, 1901. Serial No. 57,685. (No model.)

To all whom it may concern:

Be it known that I, JOHN ANGELL, a citizen of the United States of America, and a resident of St. Louis, in the State of Missouri, have invented certain new and useful Improvements in Feed-Water Heaters and Purifiers, of which the following is a specification.

The present invention relates more especially to that type of apparatus employed in steam engineering plants in which the feed-water mixed with a proportionate quantity of purge or coagulant compound is heated by contact with the exhaust-steam from the engine, after which it is passed through a filter-bed to remove the impurities and from thence into the steam-generator of the plant.

The objects of the present improvements are in the main to provide a simple and effective arrangement of the shelves within the heater-casing for effecting an intimate contact of the feed-water with the exhaust-steam and the consequent heating of such feed-water in a thorough and effective manner; also, to provide an automatic connection of apparatus and its controlling mechanisms whereby a substantially constant water-level within the apparatus is maintained during the varying conditions existing during a continued use of the apparatus, all as will hereinafter more fully appear, and be more particularly pointed out in the claims. I attain such objects by the construction and arrangement of parts illustrated in the accompanying drawings, in which—

Figure 1 is a longitudinal vertical section at line $x-x$, Fig. 2, of a feed-water heating and purifying apparatus embodying the present improvements; Fig. 2, an elevation of one end of the apparatus with parts in section at line $x'-x'$, Fig. 1; Fig. 3, an elevation of the opposite end of the apparatus with parts in section at line $x-x$, Fig. 1.

Similar numerals of reference indicate like parts in the several views.

Referring to the drawings, 1 represents a vertically-arranged closed casing or housing of any usual and approved construction and which in the present improvement constitutes a heating-chamber for effecting the desired heating of the feed-water by the exhaust-steam from the engine and a receiving-chamber for the heated feed-water and which receiving-

chamber is in turn provided with an intermediate filter-bed through which the feed-water passes to have its suspended impurities removed before being fed to the steam-generator. The casing 1 is also provided with the usual steam-inlet neck or passage 2, steam-outlet neck or passage 3, feed-water inlet-pipe or passage 4, and feed-water outlet-pipe or passage 5, extending either directly to the steam-generator or to the feed-pump by which the generator is supplied.

6 is the usual filter-bed, supported on a perforated grid 7, arranged a distance above the bottom of the casing or tank 1 so as to leave a clear-water chamber 8, with which the feed-water outlet-pipe 5 is connected.

9 is an upturned and laterally-perforated extension of the feed-water inlet-pipe 4, arranged centrally in the steam-outlet or exhaust-neck 3 of the heater-casing and adapted to discharge the feed-water in jets and in a direction transverse of the outgoing steam and against the inner walls of such neck, so that more or less of the feed-water will trickle down said inner wall of the outlet-neck and from thence down the inner surface of the heater-casing to afford an increased and effective heating and condensing surface in the operation of the present apparatus.

10 is an elongated water-receiving trough or hopper supported centrally beneath the outlet-neck 3 by end lugs 11 on the main casing and adapted to receive the feed-water discharged from the inlet-pipe 4 as such water rains down from the outlet-neck 3. Such trough is provided with a central raised web or partition 12 and a series of perforations 13 at each side of such web, the construction being adapted to divide and distribute the water in an even manner to the series of surface heating plates or shelves arranged beneath said trough and occupying the upper portion of the casing 1.

14 and 15 are alternating series of surface heating shelves or plates, the one series, 14, slanting downwardly from the center and the other series, 15, slanting downwardly from the sides, as shown in Fig. 1. Each shelf or plate will preferably consist of two straight halves meeting at the center, as shown, and the first-mentioned series 14 will be provided with passages 16 at their outward edges for

the passage downward at such points of the feed-water onto the next adjacent shelf below, while the last-mentioned series, 15, are provided with passages 17 at their center for the passage downward at such points of the feed-water onto the next adjacent shelf below, so that such feed-water will have a circuitous or serpentine passage down along the series of shelves to have an extended and effective exposure to the exhaust-steam to attain a very efficient heating of the passing feed-water. From the lowermost shelf of the series the heated feed-water drips down into the receiving-chamber therefor in the lower part of the main casing, as illustrated in Fig. 1. The series of shelves are preferably ribbed in the direction of their slant, so as to better maintain an extended separation of the feed-water flowing over the same.

20 18 represents skeleton end frames supporting the series of shelves 14 and 15 at their outer ends, and which skeleton frames are in turn supported on lugs attached to the inside of the main casing, as shown in Fig. 2. The 25 skeleton formation of the frames 18 is intended to permit of the free and effective entrance or access of the exhaust-steam to the series of shelves and to the thin stratum of feed-water flowing upon the same.

30 19 represents intermediate supporting-bars for the support of the central or middle portion of the series of shelves 14, such supporting-bars resting at one end on lugs 20 on the main casing and at the other end upon transverse bars 21, extending across the doorway 22 of the main casing and resting upon lugs at the side of such doorway, and which doorway is normally closed by a door or cover 23. In the present construction the series of shelves or 40 plates 15 are supported at their central or middle portion by upwardly-extending lugs or flanges 24 of the shelves 14, that form rests for the central edges of the halves of the series of shelves 15 and permits of the free upward 45 passage of the exhaust-steam and a contact of the same with the feed-water falling through the central openings 17 of the series of shelves 15.

50 25 is a water or grease separator secured at one side of the main heater-casing at a point above the normal water-level in the main heater-casing and having the usual arrangement of intercepting-partitions for intercepting the water, grease, &c., of entrainment carried by the exhaust-steam.

No claim is made in the present case either to the construction of the separator or the hereinafter-described arrangement and connections of the same with the feed-water heating and purifying apparatus, as such constructions and connections constitute the subject-matter of my separate applications for Letters Patent, Serial No. 57,162, filed April 24, 1901, and Serial No. 69,882, filed July 27, 65 1901. In the particular construction shown the separator-casing is provided at one side with a flange 26, by means of which it is bolted

to the side of the main heater-casing with its outlet-opening in register with the inlet-passage into such main casing for the exhaust-steam, and at the opposite side with an inlet-neck for the attachment of the exhaust-steam pipe or main, as shown in Figs. 1 and 2.

70 27 is a disk secured upon the inside of the main casing, preferably by the same bolts 75 which secure the separator in place, and formed with a cylindrical neck 28, which in turn is provided with an annular marginal flange 29. Such parts have an axial arrangement in the main inlet-orifice to the main heater-casing, as shown, and are adapted to form a very efficient barrier to prevent the usual creeping action of the water, grease, &c., of entrainment in the direction taken by the steam and into the main heater-casing to mix 80 with the feed-water and be returned to the steam-generator.

85 30 is a reticulated grid arranged in the interior of the separator casing and in the path of the incoming exhaust-steam and adapted 90 to divide or separate the exhaust-steam and direct the same in its divided condition against the imperforate impact-partition 31, so that the water, grease, &c., of entrainment will adhere to and be retained by the surface 95 of such partition, while the steam is left free to continue its travel into the heater-chamber.

32 is a passage leading downward from the separator 25 and adapted to conduct the water, grease, &c., of entrainment away from 100 the same.

33 is a receiving-chamber at the lower end of the passage 32, adapted to receive the entrainment-water, &c., and provided with a blow-off pipe or passage 34, provided in turn 105 with an automatic blow-off valve 35, operatively connected with a float 36 in said chamber and adapted to automatically open and blow off the contents of such chamber when such contents reach a predetermined level in 110 the chamber by the gradual accumulation of the entrainment-water, &c.

37 is a branch elbow pipe or passage extending into the interior of the main heater-casing, with the open end of its vertical portion on a level with the normal or predetermined water-level in said main casing. Such open end is preferably formed flaring or funnel-shaped to more effectively act as a skimmer for receiving the surface water and the 115 scum and impurities carried thereby and conduct the same down into the receiving-chamber 32 to be blown off from the same in an automatic manner along with the entrainment-water, &c.

120 38 is a cone-shaped cap located a distance above the funnel-shaped mouth of the branch passage 37 and adapted to intercept any feed-water from dropping directly into such mouth.

125 In the present invention a predetermined water-level is automatically maintained in the main heater-casing by means as follows:

130 39 is a float-chamber secured to the outside

of the main heater-casing on the same level with the normal water-line, which it is intended shall be maintained in the main heater-casing.

- 5 40 is a water-pipe extending from the lower end of the float-chamber 39 to the lower portion of the main casing and constituting a water connection between the two chambers or casings. 41 is an equalizing steam-pipe 10 extending in like manner from the top of the float-chamber 39 to the upper portion of the main heater-casing and constituting a steam-filled connection between the two chambers or casings. As so arranged the two pipes 40 and 41 will maintain the same water-level in the float-chamber as prevails in the main heater-chamber, and such pipes will be made of comparatively large size for the purpose or function hereinafter described.
- 15 42 is a rock-shaft intersecting one end of the float-casing 39 and carrying within the same the arm 43 of an operating-float 44. The end of the rock-shaft 42 outside the float-casing carries an arm 45, having link connection 20 46 with a lever 47, by which the controlling-valve 48 in the feed-water inlet-pipe 4 is regulated and controlled in an automatic manner, in that with the falling of the water in the main heater-casing below the normal level 25 48 will be opened by the automatic mechanism just described to admit a greater supply of feed-water, and as the feed-water accumulates in said main heater-chamber so as to reach the normal level the valve 48 will 30 again close or partially close to reduce the supply of feed-water. Such changes in the supply of feed-water to the heater will automatically occur responsive to the fluctuations 35 of the water-level within such main heater.
- 40 49 is a closed holder or tank for the purge or coagulant compound, of any usual shape and preferably arranged at the side of the main heater-casing in adjacent relation to the float-chamber 39 for the purpose of automatic control, as hereinafter set forth.
- 45 50 is a filling neck or opening for the tank 49, closed by a cap 51, having an operating screw-shank, a hand-wheel, and a confining-yoke 52, swiveled to the neck, as shown, the 50 described construction affording a connected attachment of parts, which permits of the same being swung out of the way and not impede the operation of filling the tank.
- 55 53 is a pipe connection or passage opening 55 into the upper part of the tank 49 and adapted to introduce a supply of water from any convenient source of water-supply having pressure sufficient to discharge the contents of the tank in the manner hereinafter described into the feed-water inlet-pipe 4 of the apparatus.
- 60 54 is an outlet-pipe connecting with the lower end of the purge-tank 49, which in my preferred construction, as shown in the drawings, 65 is extended up through the pipes 40 and 41 of the float-chamber 39 and from thence to the regulating-valve 55 and sight-feed tube

56 to the feed-water inlet-pipe 4 to discharge a regulated and limited quantity of the purge compound into the passing feed-water and 70 which amount can be regulated by the operator through the instrumentality of the regulating-valve 55 as his judgment may indicate.

75 57 is a branch or extension of the outlet or purge pipe 54 of the purge-tank, provided with a valve 58, constituting a blow-off for said purge-tank in the operation of cleaning out the same.

80 By the arrangement above described of the purge-carrying pipe 54 within the pipes 40 and 41 a heating of the passing purge compound to a temperature approaching that existing within the main heater-chamber is attained, which preheating of the purge compound I find by practical experiment increases the efficiency of the same to a very considerable extent.

85 63 is a motor-casing secured at the upper end of the purge-tank 49 and containing a 90 motor-wheel or revolute piston of any usual construction and which is adapted to operate a suitable stirrer by which the contents of the tank is kept in a state of agitation.

95 65 is the motive-fluid-supply pipe to the motor-casing, provided with a throttle-valve 69.

100 69 is a throttle-valve in the pressure-supply pipe 65, which in some cases may be regulated by hand. It is, however, preferable to control the same automatically and in unison with the water-level-control mechanism heretofore described or a duplicate of the same, if the particular circumstances may so indicate. In the drawings I have shown the throttle-valve 69 provided with a bell-crank-operating lever 70, the free arm of which is arranged in the path of a tappet 71, adjustably secured upon the link connection 46 of the heretofore-described automatic float mechanism by which the feed-water inlet is 105 controlled and regulated. The arrangement in this connection is such that with a downward movement of the float 44, responsive to a fall in the water-level in the main heater-chamber, the tappet 71 will contact with the lever 70 to open said valve 69 to start the motor-engine of the stirring mechanism of the 110 purge-tank, the operation continuing until the float 44 again rises to permit a closing of the said throttle-valve and a stoppage of the 115 motor-engine. It will be observed that by the described automatic connections the opening and closing of the regulating-valve of the feed-water inlet and the opening and closing of the throttle-valve of the motor-engine of 120 the purge-stirring mechanism takes place in unison with each other.

125 68 is the exhaust or outlet pipe from the motor-casing 63, which preferably extends to and discharges into the interior of the main heater-casing, as shown in Fig. 3 of the drawings.

No claim is made in the present case to the special construction of the purge-tank 49 or

its automatic connection with the feed-water heating and purifying apparatus, as the same constitutes the subject-matter of a separate application for Letters Patent filed by me and having Serial No. 69,883, filed July 27, 1901.

72 is a valved blow-off pipe connecting the lower end of the main heater-casing with the blow-off pipe 34 for use in cleaning out the apparatus.

10 Having thus fully described my said invention, what I claim as new, and desire to secure by Letters Patent, is—

15 1. In a feed-water heater, the combination of a main rectangular-shaped casing, steam inlet and outlet necks upon said casing, a vertical tier of shelves arranged centrally within said casing and separated from the side walls of the same by vertical steam-passages which communicate with the spaces between the shelves, and a skeleton frame carried by the main casing and affording a support for the tier of shelves each individual shelf consisting of two longitudinal halves meeting at the center, substantially as set forth.

20 2. In a feed-water heater, the combination of a main rectangular-shaped casing, steam inlet and outlet necks upon said casing, a vertical tier of shelves arranged centrally within said casing and separated from the side walls of the same by vertical steam-passages which communicate with the spaces between the shelves, and a skeleton frame carried by the main casing and provided with 30 side supporting-bars for the side edges of the shelves, and with intermediate supporting-bars for the middle portions of the shelves, each individual shelf consisting of two longitudinal halves meeting at the center, substantially as set forth.

25 3. In a feed-water heater, the combination of a main rectangular-shaped casing, steam inlet and outlet necks upon said casing, a

vertical tier of shelves arranged centrally within said casing and separated from the side walls of the same by vertical steam-passages which communicate with the spaces between the shelves, a skeleton frame carried by the main casing and provided with side supporting-bars for the side edges of the shelves and with intermediate supporting-bars for the middle portion of alternate shelves, and vertical ribs on such alternate shelves constituting supports for the next adjacent shelves above, substantially as set forth.

4. In a feed-water heater, the combination of a main rectangular-shaped casing, steam inlet and outlet necks upon said casing, a vertical tier of shelves arranged centrally within said casing, and a central superimposed distributing-trough extending the length of the shelves and provided with two longitudinal series of perforations in its bottom adapted to discharge the feed-water along the entire length of the uppermost shelf, substantially as set forth.

5. In a feed-water heater, the combination of a main rectangular-shaped casing, steam inlet and outlet necks upon said casing, a vertical tier of shelves arranged centrally within said casing, and a central superimposed distributing-trough extending the length of the shelves and provided with a central longitudinal rib upon its bottom and with a longitudinal series of perforations at each side of said rib, and which perforations are adapted to discharge the feed-water along the entire length of the uppermost shelf, substantially as set forth.

Signed at St. Louis, Missouri, this 17th day of April, 1901.

JOHN ANGELL.
